United States Patent Office

Des. 205,364
Patented July 26, 1966

205,364

HOOP STICK

Donald W. Schumm, 7204 Riverton, and Doyle C. Shady,
4916 Golfview, both of Fort Wayne, Ind.

Filed Apr. 19, 1965, Ser. No. 84,846

Term of patent 14 years

(Cl. D34—5)

Fig. 1

Fig. 2

Fig. 6

Fig. 7

Fig. 8

Fig. 3

Fig. 4

Fig. 5

FIG. 1 is a front elevational view of a hoop stick showing our new design;

FIG. 2 is a rear elevational view thereof;

FIG. 3 is a side elevational view taken in a direction perpendicular to the direction along which FIGS. 1 and 2 were viewed (the view in the opposite direction being the same);

FIG. 4 is a top end view thereof;

FIG. 5 is a bottom end view thereof;

FIG. 6 is a cross-sectional view taken substantially along the section line 6—6 of FIG. 1;

FIG. 7 is a cross-sectional view taken substantially along the section line 7—7 of FIG. 2; and

FIG. 8 is a cross-sectional view taken substantially along the section line 8—8 of FIG. 1.

We claim:

The ornamental design for a hoop stick, as shown and described.
